(57) CLAIM

The ornamental design for a tartan textile, as shown and described.

DESCRIPTION

The patent or application file contains a least one drawing executed in color. Copies of this patent or patent application publication with color drawing(s) will be provided by the Office upon request and payment of the necessary fee. The single FIGURE is a top plan view of a tartan textile showing my new design.

Exemplary colors for use with the design are: red—Pantone 18-1761 TCX, gray—Pantone 15-4306 TCX, black—Pantone 19-4008 TCX, and white—Pantone 11-0601 TCX.

1 Claim, 1 Drawing Sheet
